UNITED STATES PATENT OFFICE.

ROBERT W. DAVIS, OF NEW YORK, N. Y.

HULL CONSTRUCTION.

Application filed April 21, 1921. Serial No. 463,316.

To all whom it may concern:

Be it known that I, ROBERT W. DAVIS, a citizen of the United States, and a resident of the borough of Manhattan, in the county, 5 city, and State of New York, have invented certain new and useful Improvements in Hull Constructions, of which the following is a specification.

This invention relates in general to improvements in the hull of a ship having means of propulsion applied endwise thereto, and it appertains more especially to vessels driven by a propeller positioned at one end thereof.

15 In screw propelled ships as commonly built, the propeller is generally mounted at the stern of the hull and operates to push it thru the water. Vessels are, however, used wherein propellers are positioned both at 20 the stern and at the bow. A prevalent form of vessel at the present time, as exemplified by the boats ordinarily employed in ferry service, is equipped with a propeller at each end of the hull. In boats of 25 this character, it is the practice either to operate the propellers in unison, or the bow propeller is driven independently of the stern screw. When the bow propeller is run by a separate engine, it is found that 30 the same revolves at a relatively slower speed than the one at the stern. This is due to the retarding effect of the rushing volume of water back of the propeller being thrown against the bow of the hull, which acts to 35 impede the progress of the boat.

Theoretically, the tractor type of propeller, i. e. a screw mounted at the bow of the boat, should give better results than a propeller of the pusher species, e. g. one located at the stern, if the considerations of 40 current or stream retardation could be obviated. Besides, the rudder of the boat will function more efficiently in relatively still water than in the wash of a propeller of the 45 pusher kind, and furthermore, "squatting" at the stern of the boat, which occurs in vessels pushed thru the water, will not manifest itself to such a pronounced degree in vessels of the tractor type. Another dis- 50 advantage in vessels of the pusher class, is the dragging effect of the water at the stern produced by the propeller, which obviously will not be present in the tractor character of a boat.

55 Also, with the screw placed at the for-

ward end of the vessel, the latter is not only easier to maintain on the proper course in heavy seas, but the same will ride more smoothly and not pitch or throw the propeller out of the water to any such extent 60 as is common in ships of the pusher sort. However, to make a tractor ship practical, it is necessary to obviate or minimize the reaction of the so-called slip-stream upon the hull in order that the coaction between 65 the propeller and the hull may be efficient in pulling the vessel at desired and requisite speeds.

With the foregoing considerations in mind, the main object of the present invention is to provide a vessel of the tractor type wherein the retarding effect of the wash from the propeller on the hull will be 70 minimized.

Another object is to produce a hull of the 75 character described, in which the drag of the hull upon the water or the latter upon the former at the stern will be reduced as much as possible, and the speed of the vessel may be increased without augmenting 80 this action.

A further object is the provision of a vessel of the nature set forth whereby the stream from the propeller is equally divided on both sides of the hull and caused to 85 gather about the latter in a manner to buoy the bow thereof and prevent it from sinking too deeply, while holding the boat to a straight course.

Still another object is the production of a 90 vessel of the type specified so formed at the bow that the helical or swirling motion imparted to the water by the propeller shall be kept up as much as possible during its passage along the hull.

A still further object in producing a vessel of the class mentioned is to furnish it with deflecting surfaces so constructed and arranged that part of the water coming from a propeller mounted at the bow of the 100 hull shall be guided in a longitudinal direction by the sides of the same without undue friction or retarding action.

A general object is to supply a vessel of the genus alluded to which is thoroughly 105 sea-worthy, capable of being strongly built at reasonable cost and wherein the propelling power can be utilized with maximum advantage over the prevalent types now in use.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawings, where 10 in like parts are designated by the same reference characters throughout the several views.

In the said drawings:—

Figure I is a fragmentary side elevation 15 of the bow of a vessel showing the same constructed in accordance with the present invention, the surfaces thereof being shaded for the purpose of bringing out their configuration;

Fig. II is a view similar to the preceding, the shading having been omitted, and spaced lines substituted to represent structural elements corresponding to similar parts in the other figures;

Fig. III is an end elevation looking from the lefthand side of Fig. I, surface shading being employed to bring out the contours of the parts;

Fig. IV is a view like the last named, and 30 indicates structural elements corresponding to those shown in Fig. II;

Fig. V is a plan view looking down upon the top side of Fig. I; and

Fig. VI is also a plan, but viewed in an 35 oblique direction according to an arrow A pertaining to Fig. IV.

Generally described, the invention under consideration includes in its organization a submerged prow extending forwardly of the 40 bow of the hull from the bottom of the latter to about the light load water line thereof. This prow is given a twisted wedge shape, that is, the sides thereof have a helical formation, and the propeller shaft bearing tube passes thru the middle of the sharp end of this wedge. The top and bottom faces of the prow which may be flat for their major portions, are preferably tapered toward the same end and merge in offset relation one to the other with the edge of the wedge. This edge which constitutes the 50 stem of the prow is divided so that parts of the same are tangent to opposite sides of the propeller shaft tube. The helically formed 55 portions of the prow which lie substantially within a projected transverse plane bounded by the stem's extremities, guide the water set in motion by the propeller along the hull, while those surfaces that are situated beyond the extremes of the divided stem, serve to deflect the water which is not directly 60 acted upon by the propeller, out of the path of the hull.

The advantages of the invention as here 65 outlined are best realized when all of its

features and instrumentalities are combined in the one and same structure, but, useful devices may be produced embodying less than the whole.

It will be obvious to those skilled in the 70 art to which the invention appertains, upon becoming conversant with the details thereof, that the same may be incorporated in several different constructions. The accompanying drawings, therefore, are submitted 75 merely as showing the preferred exemplification of the invention.

Referring now to the aforesaid views of the drawings for a detailed description of the invention, the reference numeral 5 denotes the bow proper of a hull 6. Extending forwardly from the lower portion of the bow 5, is a submerged prow 7 which in practice may reach in depth from the bottom or keel of the vessel to substantially the light 80 load water line thereof.

The submerged prow 7 projects an appreciable distance beyond the remainder of the hull 6 and terminates at its forward end in a stem 8. The latter is obliquely 90 disposed with relation to a central vertical plane passing longitudinally thru the hull, as shown to best advantage in Figs. III and IV, wherein the stem 8 is illustrated as being divided so that equal parts thereof are 95 above and below a propeller shaft bearing tube 9. The upper part of the said stem extends in diagonal tangential relation to the righthand side of the shaft tube 9 in a general upward direction, while the 100 lower portion of the stem runs diagonally tangent to the said tube in a like manner, but downwardly from the left side thereof. The construction shown in the drawings corresponds to an arrangement for association with a propeller turning in a clockwise direction, looking forward from the boat.

It will be seen that a propeller shaft 11 extends thru the tube 9 beyond the forward end thereof, and has affixed to it a propeller or screw of any appropriate type, such as shown at 12 in Fig. VI. The direction of rotation of the propeller with reference to the hull construction is indicated by an arrow B in this figure. It will be understood, moreover, that any kind of engine or motor positioned within the vessel may be employed for driving the propeller, but in the layout shown, the parts as before mentioned are organized for co-operation with a screw driven clockwise. However, it will be clear that if the propeller is to be rotated the opposite way and has a corresponding pitch, the shaping of the submerged prow will be merely reversed, that is to say, the parts would be disposed so that the divided stem 8 would be inclined downwardly from the left to the right on opposite sides of the propeller tube 9 in 120 125 130

stead of from the right to the left as shown. In practice, the inclination of the sections of the stem may vary from 30 degrees to 60 degrees. Nevertheless, the angle of obliquity will depend to a large extent on the pitch of the propeller employed in conjunction with the hull structure.

The submerged prow 7 may be graphically described as of substantially twisted wedge shaped formation, since it will be noted that the opposite lateral sides or surfaces thereof diverge in helical paths from the stem sections 8, one surface winding toward the right and the other left, as viewed in Figs. III and IV.

In the hull under consideration, as best seen in the shaded Figures I, III and V, it will be noted that the portion of the submerged prow which is situated to the left 20 of the stem 8 follows the curvature of a lefthand helix 14, while that on the right conforms to a similar convolution 15, but is oppositely disposed, the two parts being arranged in the same manner as a two 25 bladed auger. At a predetermined distance aft from the stem these helices merge into the sides of the hull 6 which may be straight or of any other configuration.

The surfaces lying beyond the lines that 30 follow the adjacent differentially curved upper and lower edges of the helical portions 14 and 15 of the submerged prow and which constitute the top and bottom faces thereof, are denoted by the reference numerals 16 and 17 respectively. It will be observed from Fig. VI that a forward point 18 of the top surface 16 which coincides with the upper end of the stem 8 is bent or twisted so that a plane passing centrally 35 therethru comes at substantially right angles to the working face of the propeller 12, a like condition prevailing with reference to the surface 17 and its foremost point 19. The faces 16, 17, taken together 40 with upper and lower parts 20, 21, which are bounded by acute curved edges as shown, and pertaining to the helices 14, 15 respectively, serve in conjunction with the thereto appertaining sections of the stem 8, to 45 divide the water into two separate currents of equal magnitude, that are deflected sideways out of the way of the vessel, while the helical surfaces 14, 15, tend to maintain the swirling motion imparted to the water by the propeller, thereby facilitating its movement along the hull. This arrangement not only obviates the retarding action of the water upon the hull, but further precludes the building up of back pressure 50 immediately in rear of the propeller.

In order that the shaping of the parts may be more clearly understood, when referring to the several figures of the drawings, the structural elements constituting the 55 helical surfaces of the prow, are indicated

in sequence by the reference letters *a* to *g* inclusive and they are represented in the same order in Figs. II, IV and VI, which exemplify similar positions of the said elements. By comparing these elements in the several views, a comprehensive understanding of the configuration of the bow may be had. The centres from which the said elements radiate, are located about as far upward or downward, as they are offset outwardly from the axis of the propeller 12.

Each of the helical surfaces 14, 15 commences on lines or planes constituting prolongations of the offset and divided stem portions 8. The foremost parts of the prow 80 included between the said stem portions and their oppositely disposed prolongations have been given the reference characters 22 and 23. The latter do not necessarily partake of the helical formation of the contiguous 85 side faces 14 and 15 of which they constitute a continuation, but may be merely bent until the said parts 22 and 23 merge into their respective stem portions, the main purpose of the parts 22, 23 being to separate 90 the water coming from the propeller preparatorily to its reaching the said helical guiding surfaces. It is to be noted that the places where the deflection of the water occurs, namely, at or beyond the points 18, 95 19, that is, by the before named surfaces 20, 21, are so far offset from the vertical centre of the vessel, that the outward movement of the water, the distance it has actually to be pushed to get out of the way of the hull, is 100 considerably less, in comparison to what it would have to be moved ordinarily in a vessel having a perpendicular bow.

While the skin friction may be somewhat increased due to the higher speed of the 105 water moving past the helical surfaces 14, 15, this water is in longitudinal movement relatively to these surfaces and is not thrown directly against diagonal sides as heretofore. If the vessel were of old conventional form, 110 the water from the propeller would be thrown back against the hull and thus be required to completely change its direction of flow upon encountering the latter. Under such conditions the reaction on the hull 115 would be considerable since the propeller actually operates against itself, and in so doing impedes the progress of the ship to such an extent that an arrangement of this character is quite impractical. Aside from 120 the reaction, the building up of back pressure on the propeller is sufficient to appreciably diminish its efficiency.

For this reason, boats of the tractor type heretofore suggested have not been found 125 practical. The present invention, however, entirely overcomes the disadvantages adverted to, thru a highly efficient shaping of the prow of the hull, without complicating its construction. In practice the present in- 130

vention may be readily fabricated in hulls during the building thereof, or may be applied to vessels already constructed.

In the foregoing detailed description, the invention has been particularly described as associated with the forward portion of a ship's hull of the tractor type. Nevertheless, the principles of the construction may be utilized to advantage in boats of the combined tractor and pusher species wherein propellers are positioned at both ends of the hull, such for example, as in ferry boats. In vessels of this character, the forward portion or one end of the hull may be formed 15 in the manner specified, or both ends of the hull may be provided with the shaping herein exemplified. In practice it is deemed preferable that such a boat be furnished with a submerged prow at each end thereof, 20 so that it will operate with maximum efficiency in either direction.

Even with vessels of the pusher kind, improved results would be obtained with a stern formed according to the present invention, over one which is not provided with a twisted prow, or any of the prevailing types. Because, the water dragged away from contact with surfaces that lead the same to the propeller requires less work to be exerted thereon than when it has to leave 25 diagonally disposed sides and then become deflected by the blades of the screw. The movement of the water from the longitudinal to the helical surfaces is so gradual in a stern made according to this improved construction, that the water has time to follow the contour of the hull and is accordingly fed with greater efficiency to the propeller, which is thus afforded a better grip and effects a maximum of pushing power.

It will be understood, that when the present invention is employed in bow constructions for vessels of the tractor type, the water set in motion by the propellers, and 45 which does not pass the dividing edge or stem 8, will move in an outward direction substantially parallel thereto. This is due to a certain extent to the centrifugal force exerted by the propeller upon the water, 50 which moves outwardly in both directions and is subsequently acted upon by the surfaces 20, 21 as hereinbefore explained.

In view of the fact that the water set in motion by the propeller is diverted in equal 55 amounts to each side of the submerged prow 7, it follows that a hull constructed according to the principles described, can even under reduced speed be readily steered. Such a vessel will be of especial value in 60 canal navigation since there will be no tendency of the propelling means to draw the boat towards the nearest embankment of the canal, because the water is not sucked away from the hull, but is rather gathered around 65 it. For the same reason, a boat of this char-

acter will float lighter or have less submergence in shallow water than a stern propelled boat, which as well known always sinks deeper in a canal or other shallow body of water.

While a certain preferred embodiment of this device has been shown and described, it will be understood that changes in the form, arrangements, proportions, sizes and details thereof may be made, without departing 75 from the scope of the invention as defined by the appended claims.

Having described my invention what I desire to secure by Letters Patent and claim, 80 is:

1. A hull structure of the character described provided with diverging substantially helical surfaces, and means for propelling said hull located at the same end of the structure as said surfaces.

2. A hull structure of the character described having a portion shaped to resemble a twisted wedge, and propelling means for said structure disposed adjacent said portion.

3. A hull structure of the character described having one end thereof shaped to present spirally formed surfaces to the water, and a propeller coaxial with the axis of symmetry of said surfaces.

4. A hull structure of the character described having its bow provided exteriorly with symmetrical substantially helical surfaces, and a screw propeller mounted adjacent said surfaces in coaxial relation therewith.

5. A hull structure of the character described provided at one end with substantially helical portions, and a propeller operatively mounted adjacent said portions, the latter diverging in a direction away from 105 said propeller.

6. A hull structure of the character described provided at one end on opposite sides thereof with substantially helical surfaces, and a propeller mounted for actuation 110 adjacent the latter.

7. A hull structure of the character described provided at one extremity with a projecting portion of substantially twisted wedge formation, and a propeller mounted 115 for operation adjacent the outboard end of said portion.

8. A hull structure of the character described embodying a submerged tapered portion of substantially helical exterior, and a propeller mounted for operation adjacent the outer end of said portion.

9. A hull structure of the character described embodying at one end a submerged twisted wedge portion, a shaft extending 125 longitudinally thru the latter, and a propeller mounted on said shaft adjacent the sharp end of said wedge portion.

10. A hull structure of the character described provided at one end with a sub-

- merged projecting portion resembling a twisted wedge, a shaft extending thru the longitudinal centre of said portion, and a propeller operatively mounted on said shaft
- 5 adjacent the outer sharp edge of said wedge, said edge of the latter being obliquely disposed relatively to a vertical plane passing axially of said propeller.
11. A hull structure of the character described embodying a submerged prow of substantially twisted wedge formation, a shaft extending thru said prow, and a propeller mounted on said shaft adjacent the forward edge of the latter.
- 15 12. A hull structure of the character described having an obliquely disposed stem, a propeller located adjacent the latter, and water guiding surfaces leading in opposite directions from said stem in diverging relation to said propeller.
- 20 13. A hull structure of the character described provided with an obliquely arranged stem, a propeller disposed adjacent thereto,
- and water guiding surfaces winding oppositely from said stem in diverging relation to said propeller.
14. A hull structure of the character described having at one end a divided obliquely disposed stem, a propeller operatively mounted in proximity to the sections thereof, and helically winding surfaces diverging in opposite relation to said stem serving to guide the water to or away from said propeller.
15. A hull structure of the character described having at one end a divided obliquely arranged stem, a propeller shaft bearing tube interposed between the sections of said stem with opposite sides thereof in tangential relation to the same, waterguiding surfaces winding one right the other left hand above and below the stem, and a propeller cooperating with said surfaces mounted on the shaft journalled in said tube.

ROBERT W. DAVIS.
